United States Patent Office

Des. 193,330
Patented Aug. 7, 1962

193,330

TRUCK

Ralph G. Rutman, Allentown, Pa., assignor to Mack
Trucks, Inc., Plainfield, N.J., a corporation of New York

Filed June 9, 1961, Ser. No. 65,537

Term of patent 14 years

(Cl. D14—3)

FIG. I.

Des. 193,330

The side not shown is a mirror image of the side shown. The dominant features of my design reside in the portions shown in full lines.

I claim:

The ornamental design for a truck, as shown and described.
